UNITED STATES PATENT OFFICE.

JOHN ALDEN PLIMPTON, OF CHICAGO, ILLINOIS, ASSIGNOR TO PENNSYLVANIA CRUSHER COMPANY, OF NEW YORK, N. Y., A CORPORATION OF NEW YORK.

DEFLECTOR.

Application filed September 23, 1927. Serial No. 221,582.

My invention relates to deflectors which may be employed with coal breakers and/or cleaners of the Bradford type, such as illustrated in the patent of Borton and Hiller, 5 No. 1,086,129, dated February 3, 1914, or the patent of Hiller, No. 1,322,568, dated November 25, 1919.

In the operation of these and similar structures, coal or other material to be cleaned and broken is fed into a rotating drum forming the breaker. This drum is usually constructed of peripherally disposed screen plates which carry deflector blades serving to feed the material forward as it is carried round by the moving drum. In some instances, so-called "tailings deflectors" are employed with breakers of this type for cooperation with a tailing plow or plows; the action of which serves to govern the time the material is retained in the breaker, as well as controlling the rate of discharge of the tailings by such plow.

My improved deflector is of the universal type and may be employed as a feed deflector 25 in breaker structures of the type illustrated in the Borton and Hiller patent, referred to, or as the "tailings deflector" in a breaker structure of the type illustrated in the patent of Hiller, before referred to.

These and other features of my invention are more fully described hereinafter; reference being had to the accompanying drawings, in which:

Figure 1, is a view showing a portion of a 35 coal breaker and the manner in which my improved deflector blade may be employed therewith.

Fig. 2, is a similar view showing my improved structure employed as a "tailings" deflector.

Fig. 3, is a plan view of my improved deflector blade.

Fig. 4, is a sectional view on the line IV-IV, Fig. 3, and

Fig. 5, is a side elevation.

My improved deflector comprises a blade 1, which may have one of its ends tapered as indicated at 1^a; such blade having its body slightly enlarged intermediate its ends, as indicated at 1^b. The enlarged portion of the blade is provided with a through passage 1^c, for the reception of an anchoring bolt 2; such anchoring bolt being intended to support the deflector in its desired position in the cage or drum of the breaker relatively to the length

of the same. The base of the blade is provided with flanges 3, disposed on opposite sides of the same, which flanges may be substantially identical in contour, and such flanged portion is provided with a curved 60 slot 4; the walls of which may be on the arcs of circles struck from the axis of the anchoring bolt 2. The slot 4 is provided for the reception of a bolt 5, employed for holding the blade in adjusted positions of angularity 65 with respect to the anchoring bolt 2 securing the same to the drum.

The bolt 5 which passes through the slot 4 is designed to maintain the deflector blade at the desired angle, and in practice such bolt 70 passes through an aperture of the screen wall. Owing to its function of diverting the material carried round by the drum, the frictional hold developed by a nut secured to said bolt will not maintain the deflector blade in 75 the desired position, and in the structure illustrated in the Hiller patent, for instance, the end of the blade furthest from the relatively pivotal connection has been provided with apertured lugs for the reception of 80 bolts, which pass through and are clamped to the screen plates forming the drum structure, for the purpose of holding such deflector blade in its adjusted positions.

In the present arrangement, the curved 85 slot 4, formed in the flanged portions 3, is flanked by raised wall portions 6, the inner edges of which are angularly recessed at 6^a, in such relation as to form seats to receive the polygonal head 5^a of the bolt 5, (in the present instance square) employed for holding the deflector blade in adjusted positions, and by preference a number of oppositely disposed recesses may be employed so as to provide a plurality of seats for the head 5^a of 90 the bolt 5 and permit a relatively wide range of adjustment for said deflector blade.

The body of the deflector blade, is recessed or transversely apertured at 7, above the slot 4, to permit lifting of the head 5^a of the bolt 100 5 clear of the wall portions 6 providing the seats for such bolt head, when it is desired to shift the blade on the pivot formed by the anchoring bolt 2, with respect to said bolt 5; the nut 5^b of the latter being backed off to 105 permit such lifting.

In practice, the deflector blade is placed in the desired position on the screen plate wall of the breaker drum, and the anchoring bolt 2 set in place; its position determining 110

the axis upon which the deflector blade may be moved for the desired angular adjustments. The bolt 5 may then be placed in position; passing through an aperture in a screen plate, and its head 5^a placed in one of the seats formed by the recessed walls flanking the curved slot 4; the seat employed being the one that will give the blade in its finally secured position the desired angularity with respect to the wall of the breaker drum. Should a change in angularity be desired, the nut 5^b holding the bolt 5 may be backed off to an extent sufficient to permit the head of the bolt to be lifted from its seat and 15 into the opening 7 whereby the deflector blade may be moved on the pivot formed by the anchoring bolt 2, until a fresh seat is in registry beneath the head 5^a of such bolt 5. Further adjustment of the deflector blade 20 may be effected by shifting the position of the bolt 5 with respect to the bolt 2.

I claim:

1. The combination, with the apertured wall of a breaker drum, of a deflector blade 25 normal to said wall; said blade having a bolt hole formed in its body parallel with its side faces, a bolt passing through said opening and plate, means for securing the bolt to said plate and pivotally anchoring said blade thereto, a foot for said blade comprising laterally disposed flanges on opposite sides of the same; said flanges having a slot, a retaining bolt adapted to said slot and passing 30 through an aperture of the breaker drum wall; and a recessed lug flanking said slot and forming seats for the reception of the head of the retaining bolt whereby the latter may retain said blade in adjusted positions; said blade having a transverse opening above 35 said slot into which the head of said retaining bolt may be displaced from its seat when moving said blade on the anchoring bolt to change the angular position thereof.

2. A deflector blade adapted to be positioned with respect to the apertured wall of a breaker drum, a pivotal anchoring bolt carried by said blade and passing through said apertured wall, a retaining bolt carried by 45 said wall adjacent the opposite end of said blade; the latter having a foot with a slotted portion permitting angular adjustment of the blade with respect to said retaining bolt, and a seat adjacent said slotted portion for the reception of the head of the retaining bolt 50 whereby the latter may retain said blade in adjusted positions; said blade having a transverse opening above said slot into which the head of said retaining bolt may be displaced from its seat when moving said blade 55 on the anchoring bolt to change the angular position thereof.

3. As a new article of manufacture, a deflector blade adapted to be supported by the wall of a breaker drum and having an opening for the passage of an anchoring bolt securing said blade to said wall; said blade being movably mounted on said anchoring bolt, a foot portion formed by lateral flanges disposed on opposite sides of said blade; said flanges being provided with a slot through which a retaining bolt may be passed whereby angular adjustment of the blade on said anchoring bolt acting as a pivot may be effected, and raised portions flanking said slot and having oppositely disposed recesses 75 forming seats for the head of said retaining bolt; said blade having a transverse opening above said slot into which the head of said retaining bolt may be displaced when effecting angular adjustment of the blade. 80

4. As a new article of manufacture, a deflector blade adapted to be supported by the wall of a breaker drum and having an opening for the passage of an anchoring bolt securing said blade to said wall with an angular recess in the upper edge of the blade receiving the head of said anchoring bolt; said blade being movably mounted on the anchoring bolt, a foot portion formed by lateral flanges disposed on opposite sides of the 85 blade; said flanges being provided with a slot through which a retaining bolt may be passed whereby angular adjustment of the blade on said anchoring bolt acting as a pivot may be effected, and a recessed portion flanking said 90 slot and forming a plurality of seats for the head of said retaining bolt; said blade having a transverse opening above said slot into which the head of the retaining bolt may be displaced when effecting angular adjustment 95 of the blade. 100

5. As a new article of manufacture, a deflector blade adapted to be supported by the wall of a breaker drum and having an opening for the passage of an anchoring bolt securing said blade to said wall; said blade being movable on said anchoring bolt and having a slotted portion adjacent its opposite end through which a retaining bolt may be passed whereby angular adjustment of the 105 blade on said anchoring bolt acting as a pivot may be effected, and a raised portion flanking said slotted portion and having recesses forming seats for the head of said retaining bolt; said blade having a transverse opening above said slotted portion into which the head of said retaining bolt may be displaced when effecting angular adjustment of the blade. 110 115

In witness whereof I have signed this specification.

JOHN ALDEN PLIMPTON.
